UNITED STATES PATENT OFFICE.

LUIGI DELLA MARIA, OF TULARE, CALIFORNIA.

LOCK-ALARM.

1,391,176.

Specification of Letters Patent. Patented Sept. 20, 1921.

Application filed May 21, 1921. Serial No. 471,323.

To all whom it may concern:

Be it known that I, LUIGI DELLA MARIA, a citizen of the United States, and resident of Tulare, in the county of Tulare and State of California, have invented certain new and useful Improvements in Lock-Alarms, of which the following is a specification.

My invention relates primarily to an alarm for attachment to locks of doors or 10 any other similar closures in which a knob or lever is used to operate the lock, and the object thereof is to provide an alarm which will prevent the opening of the door or other closure without sounding the alarm.

15 A further object is to provide in a device of the above character means for regulating the violence or force with which the alarm is sounded.

20 A further object is to provide in a device of the above character means whereby the alarm may be rendered inoperative.

25 A further object is to provide a device of the above character which may be attached to any lock of the character set out without materially altering the same.

30 A still further object is to provide means whereby my alarm may be attached to or detached from the handle of a lock with a minimum amount of trouble and effort.

35 Other objects and advantages will appear herein and while I have shown and will describe the preferred form of my invention it will be understood that I do not limit myself to such preferred form but that various changes and adaptations may be made therein without departing from the spirit of my invention.

40 In the drawings accompanying and forming a part hereof:

45 Figure 1 is a top plan of my device with the bell removed for clearness of illustration, showing the device in its operative position.

Fig. 2 is a similar view to Fig. 1, showing 45 the device in its inoperative position.

Fig. 3 is a left hand end view of Fig. 1.

Fig. 4 is a top plan of my device positioned for use with a fragment of a door and the lock thereon.

50 Fig. 5 is a side elevation of Fig. 4.

Fig. 6 is a detail view of the lever connecting my device to the lock handle.

Fig. 7 is a detail view of the lever connecting my device to the handle when the alarm is made portable.

55

Referring to the drawings, my device comprises a circular disk 8 provided centrally thereof with an upwardly extending stud 9 threaded at its upper end, upon which is mounted the bell 10. Pivotaly mounted at 60 one end upon plate 8, near the upper end thereof, is an operating member 11, preferably formed of sheet metal. Member 11 is formed substantially reversed L-shaped and has pivotally mounted on its free end 12 a 65 stopper 13 in the upper edge of which is formed a step 14 and the lower edge has formed therein an arcuate space or recess 15 for a purpose hereafter described. Formed near the right hand edge of member 11 are 70

apertures 16, 17 and 18 which register with arcuate slots 19, 20 and 21 formed in plate 8, and a pin 22 is adapted to be passed through one of said slots into its companion opening in member 11 and detachably secured there- 75 in. Connected at one end to pin 22 is a metallic cord, or other flexible connection, 23, the other end of which is connected to the lower end of lever 24 extending downwardly from the operating bar of the lock. Extending upwardly from plate 8 near the upper edge is a pintle bolt 27 upon which is mounted a spiral spring 28, it being understood that the inner end of spring 28 is secured to said bolt 27. The free end of spring 28 has 80 mounted thereon a hammer 29, the lower end of which is adapted to be received in the step 14 of the stopper 13 when the device is in its operative position. A strap 30, prefer- 85

ably U-shaped, passes around hammer 29 and has its free end mounted upon bolt 27 and serves to limit the movement of hammer 29. Another spring 31 is mounted at one side of and above spring 28 upon pintle bolt 32 and has its free end 33 projecting be- 90

tween pins 34 and 35 extending upwardly from the lower edge of member 11 and serves to return said member 11 to its normal operative position as shown in Fig. 1. An additional pin 36 projects upwardly into member 100 11 at the side of pin 34 and provides means for increasing or decreasing the tension of said spring 31. Formed in the lower edge of plate 8 is a recess 36^a near the upper edge

75

95

of which is pivotally mounted a lever 37 which provides means for rendering the device operative or inoperative as desired. When the lever is in the position shown in Fig. 1 stopper 13 is held in an operative position, the step 14 engaging the lower end of hammer 29, and when in the position shown in Fig. 2 stopper 13 is permitted to drop out of engagement with said hammer. 5 A spiral spring 38 serves to retain lever 37 in its adjusted position. Mounted upon bolt 9 is a sleeve 39 provided with an angularly extending arm 40 on the end of which is pivotally mounted the lower end of regulator 41. Regulator 41 is substantially L-shaped and the lower leg 42 is formed in the shape of a beak and extends toward hammer 29. Extending upwardly from the lower end of hammer 29 is a pin 43 which is 10 adapted, when the alarm is operated, to be engaged by leg 42 and forced out of the step 14 in stopper 13 to ring the bell. Extending upwardly, and then outwardly, from the upper edge of plate 8 is a guide member 44 provided with a slot 45 in which is received a screw 46 mounted in the free end of member 41 which provides means for regulating the position of leg 42 to determine the amount of travel of the hammer 29 when 15 the device is operated. The farther the free end of member 41 is moved to the right the less travel the hammer 29 will have before being forced out of the step in stopper 13 and the less distance hammer 29 will travel 20 until stopped by strap 30, thus lessening the force with which the hammer strikes the bell and reducing the sound. The lower edge of member 44 is graduated and may be numbered or otherwise marked to indicate the 25 amount of sound desired. A thumb nut 47 is mounted on the upper end of means 46 and serves to hold member 41 securely in its adjusted position. Extending through plate 8 near the extreme right hand edge thereof, 30 are a plurality of pairs of holes 48 by means of which the securing member 49 is secured thereto by rivets or otherwise. Member 49 has a central arcuate portion 50 serving as a cover for cord 23 from the alarm to the interior of the lock. 35

In Fig. 7 I have shown my lever 24 as adapted for attachment to the handle of a lock when the device is portable. In this form the upper end is made in two halves, semi-circular in side elevation, one half being hinged to permit the same to be opened and passed around the handle of the knob outside of the lock, and a set screw is provided to clamp the same together when positioned for use. 40

It will be noted that by the use of a flexible cord 23 it is possible to mount the bell within any radius of the lock in any direction. By slight changes and adaptations it

may be adapted for use on any closure having a lock operated with a handle or knob. 65

In the operation of my device the parts will be in the positions shown in Figs. 1, 4 and 5. When the handle 51 of the lock is moved downwardly the lever 24 will be 70 moved to the right and through cord 23 will move member 11 to the right, and by means of stopper 13 will draw hammer 29 downwardly to the right until pin 43 is engaged by member 42 and forced out of the step 14 75 when said hammer will be flung to the left by spring 28 to contact with the bell 10. When handle 51 is released spring 31 will return plate 11 to its normal position, lever 37 acting to return stopper 14 to its normal 80 operative position. As shown in Fig. 2, when lever 37 is moved to the extreme right stopper 13 will drop down out of contact with the hammer 29 and prevent the bell from sounding. 85

Having described my invention what I claim is:

1. A lock alarm comprising a base plate; a spring mounted on said base plate; a hammer on the free end of said spring; an operating member pivotally mounted on said base plate; a stopper pivotally mounted on the end of said operating member and adapted to engage said hammer at predetermined times; means mounted on said base plate to normally hold said stopper in its operative position and to be moved to render said stopper inoperative; means to hold said last means in its adjusted position; a regulator pivotally mounted on said base plate adapted to release said hammer from said stopper; and means to adjust said last means to vary the travel of said hammer; a flexible connection from said operating member to a lock whereby when said lock is operated said flexible member will operate said operating member; and a bell mounted on said base plate. 95

2. An alarm for locks comprising a base plate; a spring mounted on said base plate; a hammer mounted on the free end of said spring; an operating member pivotally mounted at one end on said base plate; a stopper pivotally mounted on the free end of said operating member having a recess 115 therein adapted to receive the free end of said hammer; a pin extending upwardly from the free end of said hammer; a regulating member pivotally mounted on said base plate and being capable of adjustment 120 radially, the free end of said regulating member terminating in a beak, said beak being adapted to be moved into the path of said pin to release said hammer from said stopper; an adjusting member pivotally 125 mounted on said plate adapted to normally hold said stopper in its operative position and to be moved to release said stopper into

an inoperative position; a spring mounted on said base plate adapted to return said operating member to its operative position; a spring mounted on said base plate adapted 5 for holding said adjusting member in its adjusted position; a flexible connection from said operating member to said lock adapted when said lock is operated to operate said operating member; and a bell detachably mounted on said base plate adapted to be 10 sounded by said hammer; and means to limit the movement of said hammer.

In witness that I claim the foregoing I have hereunto set my hand this 14 day of May, 1921.

LUIGI DELLA MARIA.
